DESIGN FOR A COMBINED ASH TRAY AND LIGHTER

John F. Schylander, Chicago, Ill.

Application September 21, 1940, Serial No. 95,256

Term of patent 14 years

To all whom it may concern:

Be it known that I, John F. Schylander, a citizen of the United States, residing at Chicago, in the county of Cook and State of Illinois, have invented a new, original, and ornamental Design for a Combined Ash Tray and Lighter, of which the following is a specification, reference being had to the accompanying drawing, forming a part thereof.

Referring to the drawing:

Fig. 1 is a perspective view of a combined ash tray and lighter, showing my new design; and

Fig. 2 is a side elevation of the same.

I claim:

The ornamental design for a combined ash tray and lighter, as shown.

JOHN F. SCHYLANDER.
